DESIGN FOR A ROLL TOP DESK

Abraham Warshawsky, Detroit, Mich.

Application December 4, 1936, Serial No. 66,321

Term of patent 7 years

To all whom it may concern:

Be it known that I, Abraham Warshawsky, a citizen of United States, and a resident of Detroit, Michigan, have invented a new, original, and ornamental Design for a Roll Top Desk, of which the following is a specification, reference being had therein to the accompanying drawing, forming part hereof.

In the drawing, Fig. 1 is a perspective view of the roll top desk, showing my new design in closed position; and

Fig. 2 is a perspective view thereof, in open position.

I claim:

The ornamental design for a roll top desk, substantially as shown.

ABRAHAM WARSHAWSKY.
